PHOTOTYPE COMPOSING MACHINE

Louis A. Spievak, Atlanta, Ga.

Application June 6, 1938, Serial No. 212,145

4 Claims. (Cl. 95—4.5)

This invention relates to a phototype composing machine for photographing and reproducing lines of printed matter upon a sheet of sensitized paper or film. More specifically, it comprises a 5 magazine with a plurality of slides containing complete fonts with means for withdrawing a plurality of selected type characters from these fonts in aligned form by the action of a keyboard so that successive lines of composition may be 10 produced photographically. Means are also provided for restoring the characters to their original position in the magazine so that they may be again used. In my present invention, while the selected lines of characters are being 15 photographed, the controls for a second line may be selected from the keyboard and these controls will become usable upon the completion of the preceding line.

It is an object of this invention to provide a 20 composing machine of the class described, in which variable width characters in a justified line length are used so that the justified line may be photographed. Also means are provided for reproducing successive justified lines, one above 25 the other, on the same film.

It is another object of the present invention to obtain different sizes of reproduced type from a single size type which is withdrawn from the 30 magazine. These different sizes are obtained by suitable photographing and film displacing means, which will be more clearly described in the following specification.

It is a further object of the invention to provide a phototype composing machine with a section 35 having a plurality of slides containing complete fonts which fonts are disposed in a side by side relationship, with a second section of slides spaced apart from the first section so that different design fonts may be used in each section. This feature will add to the utility of the 40 machine in that the machine may be adapted for use with any design of type.

Some of the objects of the invention having been stated, other objects will appear as the description proceeds when taken in connection with 45 the accompanying drawings, in which—

Figure 1 is an assembled schematic view of the various mechanisms required to carry out the objects of this invention;

Figure 2 is an isometric view of a typical character body, or matrix;

Figure 3 is an isometric view of a word space character body;

Figure 4 is an enlarged isometric view of a portion of a slide in which the characters such as

shown in Figures 2 and 3 are slidably mounted;

Figure 5 is a side elevation of the upper and lower end of a slide which has the characters mounted therein, the central portion of the slide being broken away;

Figure 6 is an elevation looking at the lower end of the slide shown in Figure 5;

Figure 7 is an elevation looking at the left-hand face of Figure 5;

Figure 8 is an elevation showing a plurality of 10 slides after they have been shifted so as to bring a desired number of characters in aligned relationship;

Figure 9 is an assembled view of the aligned characters shown in Figure 8 after they have 15 been moved transversely of the slides into the rack where they are to be photographed;

Figure 10 is a sectional plan view taken through the lower portion of the slides which have been actuated and showing the position of the characters as they are being replaced to their original position within the slides;

Figure 11 is a vertical sectional view with portions thereof broken away, taken along the line 11—11 in Figure 1;

Figure 12 is a sectional view through the assembly rack and the photographing mechanism, which is shown in the central left-hand portion of Figure 1;

Figure 13 is a cycle diagram showing the timed 30 relationship between various functions.

In order to carry out the purpose of the invention in the desired manner, I employ several components, such as a keyboard, selecting mechanism, magazine, character assembling means, selector pin clearing means, photographing means, character restoring means, and energizing and controlling means. These component parts will be taken up in the order named and a detailed description of the parts will be made, 40 together with certain of their functions.

Keyboard

Referring more specifically to the drawings, 45 the numeral 10 denotes a portion of a suitable typewriter having a platen 11 and type bars 12, each of which bars are actuated by means of a lever 14 and key bar 15, it being evident that there is one key bar 15 for each character. A 50 standard key bar shift 16 is provided for shifting from lower to upper case. The typewriter is equipped with a master key 17 which operates a control valve 18 after the key bars 15 have been actuated to select the desired type. The 55

function of the master key 17 will be more fully described later.

A suitable length gauge 20 is placed in any convenient position where the operator may see the amount of space the selected characters will occupy in a line. Disposed below each key bar 15 is a plunger 22 which actuates a valve 23, said valve having an intake air supply line 24 leading thereto for conducting compressed air. Valves 23 also have communicating therewith, conduits 24 which have branch lines 25 leading therefrom, each of said lines having a valve 26 therein. Each line 25 supplies compressed air to a suitable cylinder 27 which, when filled with compressed air, 10 will move plunger 28 downwardly and rotate lever 29 and dog 30 in a counterclockwise manner to thereby rotate ratchet 31 and the associated shaft 32. This shaft has a gear 33 thereon which meshes with rack member 34, which rack has a 15 pointer 34a integral therewith disposed in front of scale 35. A tension spring 36 normally tends to move the pointer 34a to the right in Figure 1, and against a suitable stop 37 which is secured to the gauge by means of screw 37a. This stop is 20 adjustably secured to the gauge so that the length of the line may be regulated. While I have only shown two cylinders 27 and their associated parts for operating the shaft 32 and the associated rack 34, it is to be understood that there is one of such 25 parts for each basic width of character. For example, the characters in the magazine are of variable width. In a normal font the letter "i" is of six units width, the letter "m" eighteen units with, and other characters vary between these 30 limits. Where characters have the same width of course, the same cylinder 27 can be used for controlling the gauge placement.

In order to hold the indicating mechanism in traveling position, a suitable stop or dog 40 is 40 provided which can be released at the end of a line by the air which is supplied to a cylinder 42 to cause the indicating mechanism to be likewise released and returned to new line position. One end of the dog 40 is held in engaged position with 45 a ratchet wheel 31 by means of tension spring 43. In other words, when the line has been completed, air is supplied to cylinder 42 through air line 44. This air will actuate a plunger 45 and thereby rotate the dog 40 in a clockwise manner to release 50 the escapement mechanism, at which time the spring 36 will cause the pointer 34a to return to the stop 37.

Selecting mechanism

55 When a key bar 15 is pressed, the air pressure is transmitted from valve 23 through conduit 24 to a suitable cylinder 50 (see Figure 11). This cylinder has a suitable piston 51 slidably mounted therein with a pin 52 extending from said piston. 60 A compression spring 53 is disposed around the pin and normally tends to force the piston to the right in Figure 11. When air is admitted into the right-hand end of cylinder 50, the pin 52 is moved to the left which, in turn, pushes a short selector pin 55 to advanced position. It will be noted that a plurality of pins 55 are slidably mounted in a selector plate 56 and when these pins are in a normal position the ends are flush with the left-hand face of the plate. It will also be noted by 65 referring to Figure 1 that the pins 55 are aligned in vertical and horizontal rows. The pins in the vertical rows of pins are disposed so that suitable magazine slides 58 can slide downwardly in front of them when none of the pins are projecting 70 beyond the face of the plate 56. Whereas if one

of the pins 55 is actuated as shown in Figure 11 the slide 58 can only fall until the lower end thereof engages the pin.

It should be borne in mind that there are as many vertical rows of pins as there are slides 58 and the number of slides equals the maximum amount of characters desired to be used in a single line.

The cylinders 50 are disposed in a suitable selector bar 60 which is mounted for vertical sliding movement in frame 61 (see Figure 1). When a line is started, this bar 60 is disposed directly behind the first left-hand vertical row of pins 55 after which the bar advances laterally to the right a distance equal to the distance between the row of pins, for each character that is selected on the keyboard. This movement of the selector bar 60 to the right in Figure 1 is controlled by a suitable escapement mechanism. This escapement mechanism comprises a rack 62 upon which the lower end of bracket 63 is slidably supported. This bracket 60 carries selector bar 60 and its associated parts. A double acting dog 64 is secured to the lower end of the bracket 63 and is adapted to engage the notches in the lower end of the rack 62. This dog has a downwardly extending prong 64a which is actuated by a plunger 65, said plunger extending outwardly from cylinder 66. This cylinder has an internal structure similar in all respects to the structure of cylinder 50 which is shown in Figure 11 and which has been previously described. Leading to cylinder 66 is a conduit 67 which has its other end connected to valve 68, said valve being opened and closed by plunger 69. The upper end of plunger 69 is normally contacted by the free end of lever 70 which lever has a transversely disposed bar 71 resting thereon for supporting the lower side of key bars 15. It is seen that each time a key bar is depressed, the valve 68 is opened and consequently air is admitted to cylinder 66 through supply line 72 to actuate the escapement dog 64. This will allow the selector bar 60 and its associated bars to move to the right, step by step, under the tension of a suitable torsion spring 75 which spring normally rotates spool 76 in a clockwise manner to wind a ribbon 77 thereon, and thereby pull the escapement mechanism along the rack 62. In other words, each time a key bar is depressed, the escapement mechanism is allowed to move from behind one vertical row of selector pins 55 to the adjacent row of selector pins. While the selector is disposed behind each row, one pin is selected out of the row.

When the end of the line has been reached, air is automatically supplied to a cylinder 80 through conduit 81 by any suitable means such as depressing cams 275 and 272 (Figure 1). The admission of air will move a rack 82 to the left in Figure 1 and thereby cause the spool 83 to 60 rotate in a counter-clockwise manner and pull ribbon 84 and the selector assembly to the left, at the same time winding the torsion spring 75. The rack 82 is connected to the spool 83 by means of pinion 82a and shaft 83a.

It will also be noted that there is only one cylinder 50 for every two horizontal rows of pins 65; consequently, a suitable shifting mechanism must be provided whereby the selector bar 60 can be moved up or down and thereby be positioned behind the desired row of pins. The selector bar 60 has a rod 88 extending downwardly therefrom (Figures 1 and 11), the lower end of which has a piston 89 secured thereon which fits within cylinder 90. Leading from cylinder 75

90 is a conduit 91, the other end of which is connected to valve 92, said valve having a plunger 93 projecting from the upper side thereof and contacting the lower side of shift key bar 16. Air is supplied to the valve 92 by means of conduit 94. When the shift bar 16 is depressed air is admitted into cylinder 90 and thereby causes the rod 88 and selector bar 60 to move upwardly to a position where the upper horizontal row of selector pins 55 will be disposed directly in front of cylinders 50. It is thus seen that by providing such a mechanism, one cylinder can serve to actuate two horizontal rows of selector pins. This shift mechanism is comparable to the shift mechanism of an ordinary typewriter, where, as it is well known, the shift bar is actuated so as to obtain a high case letter in the alphabet or some other suitable character.

Magazine

Let us assume that the selector bar 60 has been moved from left to right as previously described to select a suitable pin from each of the various vertical rows of pins 55 in the selector plate 56. The pins will be at various elevations and when the slides 58 which have been previously described are lowered, their lower ends will rest upon their respective pin in the selector plate. The slides 58 are placed in a side by side relationship and each one of the slides has a T-shaped portion 58a integral therewith which fits into suitable grooves in magazine frame 100 (see Figures 1, 4, 5, and 10). In the position shown in Figure 1, all of the slides are disposed in their uppermost positions, with their tops flush, in which case a clamp bar 101 acts as a stop gauge for the bars and holds them in elevated position. It will be noted that these bars have a plurality of notches 102 therein which are engaged by the sharpened edge of clamp bar 101 only when the slides have been lowered. In order to release the bars 58 after a line has been selected by the selecting mechanism, it is of course necessary to move the bar 101 from beneath the lower ends of slides 58. Bar 101 is pivoted as at 103 and a suitable compression spring 104 is employed for normally forcing the bar to a supporting relationship with slides 58. The release of this bar, that is its movement to a non-supporting position, is effected by means of plunger 105, which projects outwardly from cylinder 106, said plunger contacting one end of the bar 101. This release is effected when air is supplied to the cylinder 106 through conduit 107. The release of the bars is actually effected immediately after a complete line is set on the typewriter 10.

By referring to Figures 4, 5 and 7 it will be noted that each of the bars 58 has a plurality of transversely disposed notches 108 therein, into which character bodies 109 are adapted to slide. As seen in Figure 7 when the character bodies are in their proper position the left-hand edge of the slide 58 aligns with the left-hand face of the character body. Each of the character bodies 109 has a pair of translucent members such as 110 and 111 with characters printed upon them. In the present showing, the character on the upper member 110 is of a light face type, whereas the character on the lower member 111 is of a bold face type. Since each of the bars 58 is identical and carries an identical set of characters it is evident that upon the release of the supporting bar 101 after a line has been typed, all of the character carrying bars 58 will

be allowed to fall until they reach their respective pins 55, which have been pushed out from the face of plate 56 as shown in Figure 11.

Upon the completion of the previous line, a suitable transverse elevator bar 112 will be in contact with the lower ends of the character bars 58 and in such a position to support these bars as they are lowered. The bar 112 has each end thereof secured to belts 113 which are mounted on pulleys 114, said pulleys being disposed on transverse shaft 115. The upper end of the belts 113 pass over idler pulleys such as 116 shown in Figure 11. When it is desired to return the slides into the magazine the bar 112 is moved upwardly from the position shown in Figure 1 until the lower end of the slides 58 are properly positioned within the magazine. This means for returning the slide is effected by means of pinion 117 which meshes with rack 118 which rack is actuated by a cylinder 119. When air is supplied to this piston through a conduit 120 the rack 118 is moved towards the observer in Figure 1 to thereby cause the bar 112 to move upwardly and restore the slides 58 to the position shown in Figure 1.

After a line of characters have been selected in plate 56 and it is desired to lower the various bars 58 to the desired elevation so that the slides 58 will rest upon pins 65 and the line of selected characters will be in the proper alignment, the bar 101 is released from supporting position, which will allow the lower end of the slides 58 to ride upon the transversely disposed bar 112. The weight of these sliding bars 58 will overcome friction offered by the parts of the lowering apparatus.

In Figure 8, a plurality of bars is shown in their lowered position at which time it is seen that the following characters are in aligned position, viz., "A CAB C". In other words, the above letters are the letters which were selected and which are desired to be later reproduced. With the above mentioned letters in aligned relationship, that is, with the slides dropped to a position where they will all be in the same horizontal line, it is of course evident that the notches 109 in the various slides will also be aligned; consequently, the characters may be pushed laterally and condensed into a line of predetermined length. This transferring operation will be subsequently described, but it might be stated that it is necessary to move this assembly of letters from the various slides in order to perform the desired reproducing work. Special attention is called to the word space band body 125 which also fits into a notch 108 (Figure 3). Each of these space bands has a coiled spring 126 extending from its side, which spring acts as a word spacer and expands the line to a predetermined length, thereby effecting a justification.

It will also be noted that the magazine bracket 100 has an additional row of slides 58' which are identical in all respects to the slides which have previously been described. This extra row of slides is provided in this bracket so that a different type face may be used, that is a different magazine may be moved to the position that the bars 58 are positioned in the drawings. In order to move the bars 58' to an operative position suitable screws 130 are provided which screws are rotatably mounted in lugs 100a in opposed sides of bracket 100. The screws 130 are threadably secured in lugs 131, said lugs 131 extending from the sides of supports 132. A knurled nut 133 is fixedly secured on the end of threaded rod 130.

and this nut is turned in order to move the magazine to various positions, that is, to a position where one of the two sets of vertical slides 58 and 58' will be in operative position.

5 In order to hold the slides 58 or 58' in an elevated position when that particular magazine is not in operation, a suitable plate 134 having a slot 135 therein is provided. This plate is stationary and affords a surface upon which the 10 lower end of the magazine slides which are not being used, may rest.

Character assembling means

By referring to Figures 1, 9 and 12 it is seen 15 that a rack 140 is disposed adjacent one end of selector plate 56. This rack has a groove 141 therein which is in alignment with the aligned characters which are desired to be transferred from the lowered selected vertical slides 58. In 20 the present instance, the words which must be transferred are "A CAB C". These letters are moved to the left and into the groove 141 where they are held in the position shown in Figure 9. The lateral movement is effected by a projection 25 144 which is secured on the end of rack 140. This projection is adapted to move into the aligned notches 108 in the bars 58 (see lower portion of Figure 8) and engage the right side of the aligned group of characters, after which the characters 30 are bodily pushed transversely to the left, into the groove 141. This movement is continued until the extreme left-hand character "A" engages the stop 147, said stop being mounted upon screw 148. This screw is adjustably mounted 35 in the end of the rack 140, thereby providing means whereby the position of the stop can be varied, so as to determine the point of starting of a line of reproduced type.

The energy necessary to move the rack 140 and its associated projection 144 to the left in Figure 1 is supplied by a cylinder 150, which cylinder has a vertically disposed piston provided with a rack 151, extending therefrom and engaging a pinion 152, said pinion being integral 45 with another pinion 153 which meshes with the rack 140. Whenever compressed air is admitted into the cylinder 150 through a conduit 154, the projection 144 is actuated to transfer aligned characters from the slides 58 into the rack 140 50 where they are placed in position for photographing. A compression spring 155 is disposed around the rack 140, which spring serves to return the rack 140 and its associated projection to normal position as shown in Figure 1, when 55 air pressure is released from cylinder 150.

The projection 144 has an upstanding pin 158 which pin is adapted to contact the right-hand end of line length bar 159 after the aligned characters have been moved to the desired position 60 within the rack 140 (Figure 1). The distance between the stop 147 and the right-hand end of bar 159 is the length of the line, and since word space bands 125 may be compressed to variable widths the overall length of the line can be 65 maintained constant. The line length bar 159 has a slot 160 therein which is penetrated by screws 161. After the characters have been pushed to the left in the above described manner they finally assume the position as shown 70 in Figure 9 in which position they are photographically reproduced.

Selector pin clearing means

Once the various slides 58 have been lowered 75 to their proper position so as to align the char-

acters, the clamping member 101 engages the notches 102 and holds these slides in position. After that, the pins 55 which originally limited the downward movement of the slide 58, must be restored to their normal position, that is with their ends flush with the front face of the selector plate 56. In order to accomplish this result, I have provided a projection 58b on the lower end of each slide 58. It is seen that by referring to Figures 6 and 11 that the face of this projection 58b which is adjacent the face of selector plate 56 is beveled. Therefore, when the selector plate 56 is moved to the left in Figure 1 or away from the observer in Figure 11 the pins 55, which originally limit the downward movement of slides 58 will be engaged by the beveled surfaces and pushed backwardly into the plate so that their ends will be flush with the face. Plate 56 is moved to the left in the manner just described by means of a suitable eccentric 162 20 which is mounted on shaft 163, said shaft having a lever 164 on its other end, the free end of which is connected to the upper end of plunger 165 of cylinder 166. When air is supplied to cylinder 166 through conduit 167, the eccentric 162 is rotated 25 to cause the plate 56 to be pushed to the left in Figure 1 and thereby move the selected pins 55 beneath beveled projections 58b.

It is seen that this plate has pins 168 extending therefrom which are slidably mounted in 30 brackets 169. The right-hand side of plate 56 is forced against cam 162 by means of compression springs 170. With the pins restored to their original position, a new line can be set up by the selecting means while the preceding line is 35 being photographed.

It is to be noted that by moving the pin plate 56 the cam surfaces pass over the pins 55 causing them to withdraw into the plates. The motion of the plate 56 to the side about two-thirds the 40 width of the slides 58 will carry the relative positions of the pins even beyond the cam projection 58b. Since only two-thirds of the bottom of the slides 58 will be limited by the pins (as noted by the detail of 58) it can be seen that I am 45 free to re-select the pins into stopping position, but they will not be brought back into interference position until the past line and the slides 58 have been withdrawn.

Photographing means

As previously stated, when the aligned characters are positioned as shown in Figure 9, they are ready to be photographed. Therefore, a suitable source of light 175 is provided at the back of 55 bar 140 (Figures 1 and 2) so that the light will shine through the translucent portions 110 and 111 which are secured to the character bodies 109. The upper edge of body 110 is shielded in an opaque body 116, whereas the lower edge of 60 member 111 is shielded by opaque body 117. Since bar 140 is disposed therebetween it is evident that light rays from the bulb 175 will project through a space above and a space below the 65 bar 140.

Leading to the light source 175 are wires 179 and 180, the wire 180 being secured to a suitable brush 181 which contacts commutator 182 and also contacting the commutator is a brush 183 to which is secured wire 184. A lens assembly 185 is provided and also a suitable film or other sensitized sheet 186 is provided upon which the characters are reproduced. Since the lens may be adjusted it is evident that a reduction or an 75

enlargement of the type may be had upon the film.

The lens assembly 185 has a screw 187 threadably secured therein (Figure 1) and also has a pin 188 penetrating it, both members 187 and 188 being secured in the bracket 189. The bracket 189 is pivoted as at 190. It is evident that when this bracket is pivoted about this point that both the lens assembly and the film 186 are likewise rotated. It is necessary to rotate the film and lens to the bold line position (Figure 12) when the top character bearing members 110 are photographed. When it is desired to photograph the bottom character bearing members 111 the film and lens are rotated to dotted line position. When it is desired to vary the distance between the lens 185 and the character bearing members, it is only necessary to turn the screw 187.

The film 186 is mounted upon rollers 191 and 192, both of said rollers extending from a common bracket 193. This bracket has a screw 194 threadably secured therein, the far end of said screw being loosely mounted in bracket 189. A pin 195 is also secured in bracket 189 and this pin loosely penetrates the lower end of bracket 193. When it is desired to vary the position of the film 186 relative to the character bearing members 110 and 111 and lens 185, it is only necessary to manipulate the screw 194.

After the line has been photographed it is desirable to move the film 186 downwardly to a new line position, so that the succeeding line can be printed in its proper order. This is effected by means of a toothed wheel 200 whose teeth penetrate perforations 186a in one edge of the film. This wheel is mounted upon shaft 201, which also carries ratchet wheel 202. An arm 203 is loosely mounted on the end of shaft 201, which arm carries a dog 204 for engaging the teeth in the ratchet wheel. A shield 205 is provided and this shield may be adjusted so as to determine the effectiveness of the movement of arm 203 and dog 204. For example, the farther the shield 205 is moved in a counter-clockwise manner, from the position shown in Figure 1, the less effective will be the stroke of the arm 203 and the dog 204. The arm 203 is oscillated by a plunger 208 which projects from cylinder 209. Air is supplied to this cylinder through conduit 210 when it is necessary to move the film to a new line position. The time of admitting the air is controlled by cam 218 and valve 212.

Character restoring means

After the characters have been photographed, it is necessary to return them to their original position within their respective slides 58. In order to properly return the characters to the right in Figure 1 and to release a character at each slide 58, a suitable pin 215 has been slidably mounted in one end of an arm 216 (Figures 1 and 10). One end of the pin 215 is adapted to project very slightly into the slot 141 of rack 140, and of course, when the characters are in a position to be photographed, the pin 215 will be disposed to the left of all of the characters. With the pin 215 positioned to the left of the characters, it is evident that as the pin moves to the right, all of the characters will be moved as a unit along with the pin. The member 216 has a rack 217 integral therewith, said rack being engaged by the upper side of a gear 219. This gear has integral therewith a smaller gear 220 which meshes with a vertically disposed rack 221, the lower end 75 of said rack 221 being slidably mounted in piston

222. When air is supplied to this cylinder through a conduit 223, the rack 221 is moved upwardly and, consequently, the horizontal rack 217 is moved to the right carrying therewith the pin 215, which pin also engages the group of characters which have been photographed and proceeds to push them to the right. A spring 225 is mounted around the rack 217 and normally tends to hold the pin 215 in an extreme left-hand position, but it is to be understood that when the cylinder 222 is in operation, the spring 225 is compressed.

The beveled end of pin 215 which is nearest the observer in Figures 1 and 10, is adapted to slide against one face of a bar 230. The pin 215 has a compression spring 231 confined thereto, one end of said spring being contacted by the member 216 and its other end by a pin 232. As the assembled line of characters are being returned to the various slides 58, it is very essential that means must be provided for dropping one character in each slide; consequently, notches 230a are so positioned in the bar 230, that the end of the pin 215 which is nearest the observer in the drawings will fall into one of the notches and release the character bearing body members 109 or 125 in their proper slide, after which the pin again rides out of the notch, causing the end of pin 215 farthest from the observer to again engage the left-hand side of the next succeeding member.

It will be noted that the body members 109 and 125 have beveled cavities 109a and 125a respectively therein to allow the inward movement of the pin 215 to engage another character body as the end of this pin rides out from notches 230a in the bar 230. It is thus seen that each time a notch 230a is reached, a character is automatically released in a bar 58 (see Figure 10). When the characters have been restored to their respective slides the spring 225 returns pin 215 to normal position and then the slide carrying bar 112 is moved upwardly by means previously described to restore the slide bars to the magazine bracket 100.

45

Energizing and controlling means

Air is supplied to the various pistons by a suitable compressor 240, which compressor furnishes air to the compression tank 241 from whence various leads branch. Compressor 240 is driven by shaft 242 which shaft extends from motor 243. The motor 243 also has a pulley 244 upon which belt 245 is mounted, said belt being also mounted upon pulley 246 on shaft 247. The shaft 247 is adapted to rotate constantly.

It is seen in Figure 1 that the clutch face 248 is provided which is adapted to engage another clutch face 249 upon cam shaft 250. A compression spring 251 tends to force the clutch faces 248 and 249 into an engaged position. The shaft 247 has a disk 253 thereon which disk is engaged by one arm of a bell crank 254, said bell crank being pivoted as at 255 to a support 256. The other arm of the bell crank 254 has a roller thereon which is adapted to contact side cam 257 which cam is mounted on cam shaft 250. A spring 260 normally tends to hold the roller in engagement with the side cam. After the side cam 257 has once rolled beneath the roller, the bell crank 254 is rotated in a counter-clockwise manner, which will cause the latch 261 to engage the hook 254a to latch the clutch faces 248 and 249 in a disengaged position. The parts remain in this disengaged position while the characters

are being selected in the pin board 56, but after the line of characters has been selected, that is the pins 55 pushed outwardly beyond the face of the board, the latch 261 is released to allow the 5 clutch faces 248 and 249 to become engaged, after which the cam shaft 250 is rotated one complete revolution. Latch 261 is released by means of a plunger 264 projecting downwardly from cylinder 265. The air line 266 connects the 10 cylinder 265 to valve 18.

After a line has been selected by depressing the key bars 15, the button 17 is pushed in Figure 1 to thereby cause air to be admitted to cylinder 265 for releasing the latch 261, this will allow the cam shaft 250 to make one complete revolution to carry out all of the above enumerated 15 functions. At the same time air is also admitted to the piston 42 through conduit 44 to release the latch 48 and allow the indicating mechanism 34 and 34a to return to normal position. Air is supplied to the valve 18 from the tank 231 by 20 means of conduits 270.

Leading from the compression tank 231 is a conduit 271 which supplies air to a plurality of 25 valves 272, there being a valve for each one of the cams 273, 274, 275, 276, 277, 278 and 279. also there is a plunger 280 for each of the valves 272, and these valves contact the above enumerated cams. During one revolution of the cam 30 shaft 250, all of the cams actuate their respective valves to perform the functions in timed relation.

Operation of the apparatus is as follows

35 After the operator has completed the typing of a line of composition upon the keyboard, he immediately punches the master switch 17, which causes the clutches 248 and 249 to engage and rotate the cam shaft 250 one complete revolution. During this revolution, the following mechanisms act successively in the order named.

F. Master switch 17 is pressed and a cycle begins.

G. Line gauge 34a returns. Clamp cam 273 acts to operate clamp 101 for releasing the slide bars 58 which normally rest thereon.

H. Clamp 101 is again released engaging the V-notches 102 in the slide.

I. The plate shift cam 274 acts to shift plate 56 laterally.

J. Selector bar 60 returns to new line position by virtue of cam 275.

K. Transfer member 144 acts under the influence of cam 276.

65 L. Commutator exposure occurs by virtue of cam 102.

M. Letters are returned to respective slides by the restorer pin 215, which is actuated by cam 277.

60 N. Film line space shift occurs as a result of cam 278 being actuated.

O. Clamp bar 101 is then released by another ridge on cam 273, so that the bars 58 can be restored to the magazine.

65 P. Elevator bar 112 acts under the influence of cam 279 to return slides to magazine.

Q. Clamp bar 101 is in a position to hold a bar within the magazine, cam 273 performing this function.

70 R. Cam shaft 250 is then released from the driving means thus ending the cycle.

The above enumerated operations are illustrated in Figure 13 and occur in successive order, the successive steps being indicated by the letters F to R, inclusive, in Figure 13.

In the drawings and specification, there has been set forth a preferred embodiment of the invention and although specific terms are employed, they are used in a generic and descriptive sense only, and not for the purpose of limitation, the scope of the invention being set forth in the appended claims.

I claim:

1. Apparatus for producing a photographic record of justified lines of characters comprising a plurality of individually slidable members some of which carry a plurality of characters and being slidable laterally of the slidable members, a keyboard, means operable by the depression of the keys in the keyboard for moving the 15 slidable members a predetermined amount to align a plurality of the characters in the slidable members, means operable upon selection of the desired characters for a line for moving the selected characters laterally in a body with relation to the slidable members, means for making a photographic reproduction of the line of assembled characters when they are moved laterally of the slidable members, some of the characters being compressible as to their width, 20 and means for applying pressure to the line of assembled characters to thereby regulate the length of the line, the plurality of type characters being for the same character but presenting different forms of the character. 30

2. Apparatus for producing a photographic record of justified lines of characters comprising a plurality of individually slidable members some of which carry a plurality of characters slidable laterally of the slidable members, a keyboard, means operable by the depression of the keys in the keyboard for moving the slidable members a predetermined amount to align a plurality of the characters in the slidable members, means operable upon selection of the desired characters for a line for moving the selected characters laterally in a body with relation to the slidable members, means for making a photographic reproduction of the line of assembled characters when they are moved laterally of the slidable members, means for restoring the characters to their respective slidable members and for restoring the slidable members to original position after the photographic record has been made, some of the characters being compressible as to their width, and means for applying pressure to the line of assembled characters to thereby regulate the overall length of the line, the plurality of type characters being for the same character but presenting different forms of the character. 45

3. Apparatus for producing a photographic record of lines of justified characters, as used in printing, comprising a magazine having a plurality of individually slidable bars, each bar carrying a plurality of members movable laterally of the slidable bars, some of the movable members having two forms of a given character thereon, means for selectively moving said slidable bars to align a plurality of movable members, some of said movable members having compressible means associated therewith, means operable upon actuation of a plurality of the slidable bars for moving the movable members laterally of the slidable bars and applying a predetermined pressure thereto to form a line of predetermined length, means operable upon movement of the movable members to assembled position for making a photographic record of the line of characters. 60

4. Apparatus for producing a photographic record of lines of justified characters, as used in printing, comprising a magazine having a plurality of individually slidable bars, each bar carrying a plurality of members movable laterally of the slidable bars, each movable member having two forms of a given character thereon, means for selectively moving said slidable bars to align a plurality of movable members, said

10 movable members having compressible means

associated therewith, means operable upon actuation of a plurality of the slidable bars for moving the movable members laterally thereto to form a line of predetermined length, means operable upon movement of the movable members to assembled position for making a photographic record of the line of characters, and means for selectively photographing either of the characters on each movable member. 5
